FOLDING BED AND SOFA.

No. 507,576.

Patented Oct. 31, 1893.

UNITED STATES PATENT OFFICE.

GEORGE ZISLSPERGER, OF WINONA, MINNESOTA.

FOLDING BED AND SOFA.

SPECIFICATION forming part of Letters Patent No. 507,576, dated October 31, 1893.

Application filed March 30, 1893. Serial No. 468,341. (No model.)

To all whom it may concern:

Be it known that I, GEORGE ZISLSPERGER, a citizen of the United States, residing at Winona, in the county of Winona and State 5 of Minnesota, have invented a new and useful Folding Bed and Sofa, of which the following is a specification.

My invention relates to improvements in folding-beds; the objects in view being to 10 provide a convenient and ornamental cabinet-bed, which when elevated out of operative position will form an attractive piece of furniture as well as provide a convenient sofa, and when lowered will automatically withdraw 15 the sofa from position for use and automatically lock itself in such lowered position and against accidental re-elevation.

With these and other objects in view the invention consists in certain features of construction hereinafter specified and particularly pointed out in the claims.

Referring to the drawings:—Figure 1 is a front elevation of the bed folded. Fig. 2 is a similar view of the bed lowered. Fig. 3 is 25 a transverse vertical sectional view through the bed. Fig. 4 is a perspective view of the guide-plate. Fig. 5 is an inner elevation of the side wall of the cabinet, the bed-frame being shown by dotted lines. Fig. 6 is a detail view of the rear end of one of the sides 30 of the bed frame.

Like numerals of reference indicate like parts in all the figures of the drawings.

In practicing the invention I construct a 35 cabinet-casing which consists of the back 1, the opposite sides 2, and the crown or cap-section 3, said sides having their lower portions extended beyond their upper portions forming the side-arms 4, and connected by 40 a cross-bar 4^a. At one side of the casing there is built a dresser 5, to which access 45 may be had through the medium of a convenient door 6, that may be ornamented in any suitable manner and provided with a mirror 7. The interior of the dresser may be suitably partitioned or divided, and the door upon its exterior is provided with a bracket 8 for supporting such toilet articles as are necessary. Below the shelving and within the 50 dresser a jewel-drawer 9 is located, and below this a larger drawer 10, that may serve for any useful purpose. Of course if desired

this dresser may be omitted, as it forms no operative part of the folding-bed and sofa combined, but merely a convenient accessory 55 thereto.

To the inner faces of the sides 2 adjacent to and parallel with the back 1 of the cabinet, cleats 11 are secured, the same combining with said back to form vertical ways 12, 60 and the upper ends of said cleats are provided with curved recesses 13. Above the cleats and in front of the same springs 14 are located. These springs have their front ends terminating in eyes 15 through which screws 16 are 65 passed, whereby they are secured to the side walls 2, then extended rearward over supporting-screws 17 to a point adjacent to the back, are given a coil 18, and rebent below the same 70 to form the curved arms 19, which extend to points immediately in rear of the vertical cleats 11 where they terminate in bent ends 20. Below the springs in front of the cleats 11 and to the inner sides of the sides 2 cast-metal guide-plates 21 are secured. These guide-plates 21 75 are provided upon their upper edges with horizontal tracks 22, and upon their inner faces below the tracks with cam-grooves 23. Suitable screw-holes are provided in the plates, and through these screws are passed 80 into the sides 2 and arms 4, whereby said guide-plates are secured in position.

The bed-frame consists of the bottom 26, the sides 27, the head-board 28, and the foot-board 29. The rear corners of the bed-frame 85 are provided with trunnions 30, which trunnions have anti-friction rollers loosely journaled thereon, the same being adapted to ride in the vertical ways 12 heretofore mentioned, and the upper sides or edges of the sides 27 90 receive, when they are elevated to a sufficient degree, the lower bent ends 20 of the springs.

Bearing-pins 31 extend from the sides 27 adjacent to the rear end of the bed-frame, and upon these pins loose grooved rollers 32 95 are mounted, the same being designed to ride upon the upper horizontal edges or tracks 22 of the guide-plates when the bed-frame is swung up or down to fold or unfold the same.

Bell-crank levers 33 are pivoted as at 34 to 100 the inner sides of the side-bars 27 of the bed-frame, and in rear of the same and mounted loosely in keepers 35 with which the bed-frame is provided at its opposite side-angles

are mounted reciprocating-rods or bolts 36, whose front ends terminate in eyes 37 and are connected by links 38 with the rear branches of the bell-crank levers 33. The 5 rear extremities of these bolts 36 are provided with outwardly bent ends 39 which extend through slots 40 formed in the sides 27 of the bed-frame and take into the cam-grooves 23 of the guide-plates 21.

10 Hinged as at 41 to the front lower corner of the bed-frame is a pair of legs 42, said legs being connected by a cross-piece 43 which is located below the foot-board and is adapted to abut at its upper edge against a molding 44 with which the foot-board is provided, said legs being loosely connected by links 41^a to the outer ends of the bell-crank levers. In this cross-piece a T-shaped shank 45 is swiveled, and the same is connected eccentrically 15 with a locking-disk 46. By turning the shank the locking disk may when the cross-piece 43 is in a vertical plane with the foot-board of the bed engage in a recess or keeper in the molding, or *e converso*, when the bed is elevated the locking-disk will be thrown into engagement with a similar keeper formed in the under side of the crown-piece or cap 3 of the cabinet. By this it will be seen that either the legs may be locked in position, 20 that is when the bed is lowered, or the bed locked in vertical position when not in use, all by the same lock. The cam-grooves in the guide-plates are curved as shown, and, as before stated, the outer bent ends of the locking-bolts ride therein, so that, as will be obvious, by an elevation of the bed the locking-bolts are withdrawn inwardly and through the medium of the bell-cranks the swinging-legs are folded flat against the under side of 25 the bed bottom 26. Furthermore, when the bed is swung outward the locking-bolts moving in the same grooves have a contrary effect upon the legs, that is operating them through the bell-crank levers, said legs are swung to 30 a vertical position, whereby they are adapted to support the outer end of the bed-frame. The cross-strip and the legs may be given any suitable shape or design and when in position against the external surface of the bed-frame they serve as an ornamentation to the 35 same.

40 The bed-bottom, it will be understood may be paneled or otherwise ornamented, or if desired may be provided with mirrors, and at 45 a point between the arms 4 is provided with an upholstering 47, which constitutes a sofa-back. Below the upholstering a pair of bracket-arms 48 are secured to the opposite sides of the bed and project forward there- 50 from, and said bracket-arms are provided at their outer extremities with bearing-perforations 49.

55 50 designates a rectangular seat or sofa, the same having a suitably upholstered portion 51 and of such length as to fit between the arms 4 of the cabinet and the bracket arms 48 of the bed. Pins 52 project from the

ends of the frame and take into the bearing perforations 49 of the bracket-arms 48, whereby, as will be obvious, the sofa-frame is pivoted. Bearing-pins 53 extend from the opposite ends of the sofa-frame in front of the bearing-pins 52 and upon the former pins are loosely journaled grooved rollers 55. These rollers ride upon opposite curved tracks 56, 75 which are secured to the inner faces of the arms 4 of the cabinet near the bottoms thereof.

80 A shelf 57 may be located upon a bracket 58 secured to the back wall 1 of the cabinet, said shelf being designed to accommodate any 85 desired articles. Below the shelf a mosquito-bar 59 is secured to the back 1, but may be omitted, and to this mosquito-bar is connected the upper end of the netting 60. The lower end of the mosquito-netting may be 90 removably connected with a series of small hooks.

95 The bell-crank levers are preferably covered and protected by means of shallow sheet-metal housings.

100 The construction of fastening which I describe as being located at the foot of the bed-frame for the purpose of locking said frame in a vertical position or locking the legs in operative position is duplicated preferably in 105 each of the drawers of the dresser as well as the hinged door thereof, though other forms of locks may be employed in lieu thereof, as desired.

110 The operation of the bed will be readily understood from the foregoing description and may be briefly stated as follows:—To unfold the bed from the position shown in Fig. 1 the T-shank is rotated until the locking-disk disengages from the cap-piece of the cabinet. 105 By starting the bed, that is giving it a slight pull outward at the top, the same slowly descends, the said sofa-frame riding upon its rollers and upon the curved tracks provided therefor folds against the bottom of the bed 110 and disappears from view thereunder. By this time the bed at its upper edge will have arrived in contact with the springs, which springs yield to the weight of the bed and serve to lower the same gradually to the 115 floor. When the bed has reached this position the rollers at the rear corners of the same that move in the guides 12 will rest in the curved recesses or seats 13 of the cleats 11; the reciprocating-bolts will have been operated by the grooves in the guide-plates so that the legs at the front end of the bed will be swung outward to a vertical position, and it remains simply to rotate the T-shank and lock said legs. It will be seen that the rear 120 or bent ends of the reciprocating-bolts will lock the bed against accidental raising and hence any accident on this account will be avoided. When it is desired to refold the bed it is simply necessary to rotate the T- 125 shank until the locking-disk disengages with the keeper and give a start upward when the legs will be folded by the action of the reciprocating-bolts moving in the guide- 130

slots or grooves and the springs will exert a tendency to throw the bed to a vertical position. When this position has been reached the T-shank is again rotated so as to lock the parts. As the bed ascends to assume the vertical position it will be obvious that the sofa-frame moving upon its track will be brought to the front so as to perform the functions of a sofa.

10 From the foregoing description in connection with the accompanying drawings it will be seen that I have provided an extremely simple as well as desirable and convenient piece of furniture combining in its make-up 15 a comfortable sofa, a bed, and if desired, a dresser.

It will be obvious that numerous changes in the details of construction of my invention will readily suggest themselves to the skilled 20 mechanic and persons conversant with this class of inventions, and I therefore do not limit the same to the minor details of construction herein shown and described.

Having described my invention, what I 25 claim is—

1. In a folding-bed, the combination with a cabinet, and upper and lower tracks arranged therein and at the sides thereof, of a bed-frame, rollers at the sides of the frame engaging with the upper track, bearings at the front of the bed-frame, a sofa pivoted in the bearings, and rollers at the sides of the sofa engaging the lower tracks, substantially as specified.

35 2. In a folding-bed, the combination with a cabinet casing, vertical guides therein, upper and lower guide-tracks in front of the vertical guides, the lower guide-tracks being curved, of a bed-frame having rollers at its 40 rear corners engaging the vertical guides, opposite side rollers engaging the upper tracks, bearing-brackets extending forwardly from the bed-frame in rear of the rollers that engage the track, a sofa-frame pivoted in the 45 brackets, and rollers arranged on the ends of the frame and mounted for movement on the curved lower tracks, substantially as specified.

3. In a folding-bed, the combination with 50 the cabinet, the vertical guides, the springs arranged above the guides and terminating in curved arms having bent ends, and a pair of opposite front horizontal guides, of a bed-frame having rollers at its rear corners engaging the vertical guides and in front of the same rollers for movement upon the tracks, the sides of the bed-frame being arranged in line with the springs and adapted to receive the bent ends thereof when the rear end of 55 the bed-frame is elevated to a certain point, substantially as specified.

4. In a folding bed, the combination with a cabinet having the curved tracks 56 at the

sides near the bottom, of the swinging bed frame provided with bearings, a sofa 50 pivoted in the bearings, and rollers at the sides of the sofa riding on the tracks, whereby the sofa is swung in and out on the tracks by the movement of the bed frame, substantially as described.

5. In a folding bed the combination with the cabinet casing having the vertical guides, and the springs 14 arranged above the same and secured at their upper ends to each side of the casing and having their lower ends 75 bent to form the curved arms 19 which terminate in bent ends 20 immediately in rear of the vertical guides, of the swinging bed frame having trunnions working in the guides and adapted to have the upper edges of its 80 sides received by and engaged with the ends 20 of the springs, substantially as described.

6. In a folding bed, the combination with the cabinet casing having the vertical guides, and the guide plates 21 provided with the 85 tracks 22, and the cam grooves 23, of the swinging bed frame having trunnions working in the vertical guides and provided with rollers 32 running on the tracks 22, the pair of hinged legs; a connecting piece between 90 the legs, the reciprocating bolts 39 guided on the bed frame and having bent ends engaging the cam grooves, and connections between the bolts and the legs, whereby the movement of the bed frame is caused to operate the legs, 95 substantially as described.

7. In a folding-bed, the combination with the cabinet having the rear vertical guides, the opposite pair of guide-plates having upper horizontal tracks and below the same 100 cam-shaped grooves, and the lower tracks arranged below the guide-plates, of a rectangular bed-frame having rollers at its rear corners engaging the vertical guides, opposite side rollers located upon the bed-frame and 105 mounted on the horizontal guides, a sofa-frame loosely connected to the bed-frame, rollers on the ends of the same engaging the lower curved tracks, a pair of horizontal legs, bell-cranks pivoted to the inner sides of the 110 bed-frame, links between the outer ends of the bell-cranks and the legs, a pair of reciprocating-bolts, and connections between the same and the rear ends of the bell-cranks, the rear ends of said bolts being laterally bent 115 and passed through slots in the bed-frame and engaging with the cam-grooves of the guide-plates, substantially as specified.

In testimony that I claim the foregoing as my own I have hereto affixed my signature in 120 the presence of two witnesses.

GEORGE ZISLSPERGER.

Witnesses:

EDWARD LEES,
JOHN DIETZE.
